CUTTER FOR THE INSULATION OF CABLES

Anthony Carta, Los Angeles, Calif., assignor to Taca
Cable Stripper Mfg. Corp., Los Angeles, Calif., a cor-
poration of California

Application February 20, 1956, Serial No. 566,618

11 Claims. (Cl. 30—91)

This invention relates to a tool for cutting through the sheath or insulation of cables to enable removal of the sheath or insulation thus severed.

An object of the present invention is to provide a tool of the character referred to that is adjustable between two operative positions to cut circumferentially through a cable sheath and/or to slit the same, as desired. In practice, both cuts are made—the circular or circumferential cut first—so that the sheath part thus severed may be easily removed from the cable.

Another object of the invention is to provide a tool having novel and improved cable gripping means, the same greatly facilitating the mentioned adjustment between circumferential cutting position and longitudinal slitting position.

A further object of the invention is to provide a tool of the character indicated that embodies novel and improved cutter means, the particular features of which are facile adjustability for depth of cut and ease of replacement when desired.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes, one embodiment of the present invention, which is given by way of illustration or example only.

In the drawings, like reference characters designate similar parts in the several views.

Fig. 1 is a longitudinal sectional view of a cutter tool according to the present invention and shown in circular or circumferential cutting position.

Fig. 2 is an end view of the tool as in Fig. 1.

Figs. 3 and 4 are cross-sectional views as taken on lines 3—3 and 4—4, respectively, of Fig. 1.

Fig. 5 is a side elevational view of the tool showing the same in longitudinal cutting position.

Fig. 6 is an end view of the tool as in Fig. 5.

Fig. 7 is a cross-sectional view as taken on line 7—7 of Fig. 5.

Fig. 8 is an enlarged cross-sectional view as taken on line 8—8 of Fig. 3.

The sheath cutting tool that is illustrated comprises, generally, a body 10, longitudinally adjustable cable-locating means 11 carried by said body, transversely rotational adjustable means 12 between the body 10 and the cable-locating means 11, a cutter means 13 carried by the body and axially adjustable relative to the cable-locating means 11, a cable clamp 14 cooperating with said means 11 and carried by the cutter means, said cutter means 13 embodying automatic locking means 15, when in projected or cutting position, and finger-touch release means 16 for said locking means.

2

The body 10 is preferably integrally provided with a handle 20 and has a through bore 21 formed therein, the same terminating in a counterbore 22. The end of the body having the counterbore is closed by a plate 23. Said plate and the opposite end of the body are each provided with a cylindrical extension 24, the same constituting aligned trunnions. A threaded bore 25 extends at an angle from said opposite end of the body and opens into the counterbore 22. Also, said body carries a spring ball detent 26, the same preferably being located at said opposite end, as indicated in Fig. 8.

As can be seen from Fig. 4, said body 10 is generally rectangular in form, except that one corner thereof is rounded over, as at 27, to form a quarter round that has its curvature generated on the center of bore 21.

The cable-locating means 11 is shown as comprising a base 28, an elongated bracket arm 29, a fastener screw 30 for separably securing said base and arm in longitudinally adjustable position, a cable engaging and centering roller 31 carried by the extending end of arm 29, and a finger loop 32 carried at the end of said roller.

The base 28 preferably is formed to have a channel 33, the same being adapted to receive the arm 29 for longitudinal adjustment. By providing the base 28 with a plurality of tapped holes 34 and said arm with a plurality of clearance holes 25, the screw 30 may be used to lock the adjustment of said arm relative to the base by a suitable selection and alignment of tapped and clearance holes.

The arm 29 carries a pin 36 at its end remote from the holes 25 and, intermediate its ends, said arm is provided with an outwardly bowed portion 37. The roller 31 and loop 32 are rotationally carried by pin 36, the former being so grooved as to define a cable-nesting socket to hold a cable C in line with the center of bore 21, and the latter comprising an angularly bent ring independently rotational on pin 36.

Since the arm 29 holds the roller 31 forward of the body 10, the bow 37 in said arm is disposed in the space between said body and said roller 31. Therefore, cables of different diametral size may be accommodated in said space without interference with arm 29.

The means 12 interconnects the body 10 and the base 28 and is here shown as comprising a pair of similar bracket plates 38 that are fastened to base 28 and have aligned bores 39 into which the trunnions 24 extend. It will be clear that the means 11 is capable of being rotated on said trunnions between the position of Figs. 1 and 2 and that of Figs. 5 and 6, the quarter round 27 allowing said rotational movement and the detent 26 retaining the adjusted position.

The cutter means 13 is best seen in Figs. 1 and 8 and is shown as comprising a housing tube 49 slidably mounted in bore 21, said tube being provided with a head 41 at the end directed toward the roller 31 and with external threads 42 at the opposite end. The bore 43, adjacent the headed end, is first reduced, as at 44, and then is connected into a longitudinal slot 45 that passes through the headed end. In the bore 43 is disposed a spring abutment 46, the same being retained against endwise movement as by a lock screw 47 carried by the body 10. Behind the abutment 46 there is provided a coil compression spring 48. The abutment 46 is shown as a tube, the bore of which is aligned with and approximately the same size as the reduced bore 44.

A knife blade-carrying rod 49 is slidably carried in said aligned bores, the same having a head 50 on the end thereof that extends toward and beyond the threaded end of housing tube 40. The opposite end of said rod is provided with a notch 51 that opens at the side and is spaced from the tip of said opposite end. The notched portion of the rod 49 is guided in reduced bore 44.

A blade 52, having a point 53, has hooking engagement with the notched end of rod 49 and is held by said rod so as to extend into and through the slot 45 of the housing tube. It will be seen that said slot holds the blade aligned with the rod 49 and that said blade is movable longitudinally in slot 45 according to the longitudinal adjustment of the rod relative to the housing tube.

The threads 42 of the housing tube 40 carry an adjusting nut 54 that is interiorly hollow and is adapted to abut the head 50 of rod 49. A nut 55 locks the adjustment of said nut 54. Thus, the rod 49 is adapted to be projected against the biasing or return force of spring 48 since said spring is confined between the abutment tube 46 and said head 50. Such projection of rod 49 causes protrusion of the blade point 53 beyond the face of head 41 of the housing tube 40.

Although the blade is longitudinally adjustable relative to the housing tube, as above, the spring 48 biasing the blade also provides a biasing force that holds the housing tube retracted in a direction away from the cable-centering roller 31. This retracted position of the housing tube is the normal one and provides clearance for application of the tool to a cable for cutting into the sheath thereof.

The cable clamp 14 is shown as flange-like member 56 that has a collar extension 57 which fits over the housing tube and serves as a retractive abutment for the cutter means 13 by engaging the end of the trunnion 24 on that side of the housing 10. The head 41 of the housing tube fits into a counterbore on said member 56, the face 58 thereof being substantially flush with the outer face of head 41 and being directed toward the roller 31. Said outer face is provided with a set of bearing balls 59 that are in symmetrical arrangement around the axial center of said member 56 and cooperate with roller 31 to clamp a cable C when the cutter means 13 is projected.

The counterbore 22 houses the automatic locking means 15 which is shown as a lock plate 60 through which the housing tube 40 extends and which is biased by a spring 61 in a direction to wedge tube 40 against retractive movement. Thus, projection of the tube 40 is easily effected by an endwise push on nut 54 and the means 15 maintains such projection automatically. The dot-dash lines of Fig. 1 show such projection.

The means 16 effects release of the projected housing tube and, therefore, release of the cable C. Such release is effected by a plunger 62 that has a normally-retracted spring-biased position in a guide tube 63 threadedly engaged in the bore 25. Said plunger 62 is in position to engage and move the spring-biased end of lock plate 60 when a finger is pushed against the head 64 of plunger 62.

In the position of the tool in Figs. 1 and 2, the knife point 53, after proper protruded adjustment, will make a circumferential cut 65 through a sheath around the cable C. Then, by adjusting the tool to the position of Figs. 5 and 6 and by using both the handle 20 and the loop or ring 32, the cutter point 53 may be drawn longitudinally along the sheath in the direction of arrow 67 to slit said sheath. Thus cut and slit, the sheath portion 66 may be easily peeled away from the cable even if the same comprises a metal, such as lead.

On all soft sheathed cables, after making the circumferential cut, the blade point may be left in the sheath while the adjustment to the position of Figs. 5 and 6 is made. It is preferred that said point be retracted when making such adjustment for lead sheaths and the like.

While the foregoing has illustrated and described what is now contemplated to be the best mode of carrying out my invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described my invention, what I claim and desire to secure by Letters Patent is:

1. A tool of the character described, comprising a body having a handle, a bracket arm having a rotationally adjustable two-position connection with said body, cable-centering means carried by said arm in endwise relationship to said body, and cable-clamping and -cutting means carried by the body and axially movable toward and from the cable-centering means to clamp and cut a cable in both positions of the cable-centering means.

2. A tool according to claim 1: said tool being circumferentially movable around a cable, in one of said two positions, to cut a circumferential groove in the sheath of said cable, and longitudinally movable relative to the cable in the other position to longitudinally slit said cable sheath, and a finger loop carried by the cable-centering means and cooperating with the handle to effect such longitudinal movement of the tool.

3. A tool adapted to both circumferentially cut into the sheath of a cable and longitudinally slit said sheath between said cut and the end of the cable, said tool comprising a body provided with projectable cutting means, the latter carrying a cable clamp, cable-locating means relative to which said cutting means and clamp are projectable, and means mounting said cable locating means on the body and having two positions rotationally relative to the cutting means.

4. A tool adapted to both circumferentially cut into the sheath of a cable and longitudinally slit said sheath between said cut and the end of the cable, said tool comprising a body provided with projectable cutting means, the latter carrying a cable clamp, cable-locating means relative to which said cutting means and clamp are projectable, and a two-position rotationally adjustable base connecting the cable-locating means to the body.

5. A tool adapted to both circumferentially cut into the sheath of a cable and longitudinally slit said sheath between said cut and the end of the cable, said tool comprising a body provided with projectable cutting means, the latter carrying a cable clamp, cable-locating means relative to which said cutting means and clamp are projectable, and a two-position rotationally adjustable base connecting the cable-locating means to the body, and means provided in said base to adjust the cable-locating means longitudinally relative to the end of the body.

6. A tool according to claim 3: the body being provided with aligned trunnions on the axis of projection of the cutting means, and the mounting means including bracket members rotationally engaged with said trunnions, said member mounting the cable-locating means.

7. A tool according to claim 4: said two-position base comprising aligned trunnions on the axis of projection of the cutting means, and a pair of bracket members rotationally engaged with the trunnions, said members mounting the cable-locating means.

8. In a tool for cutting into the sheath of a cable, the combination comprising a body, a tubular member axially movable in the body, a spring-biased rod disposed on the axis of said tubular member, a cutter mounted at one end of said rod, and finger-adjustable means carried by the tube to adjust the axial position of the cutter in respect to an end of the tubular member.

9. In a tool according to claim 8: in which the rod extends substantially the full length of the tubular member, and the finger-adjustable means is carried by the end of said tubular member that is opposite to the end from which the cutter is protruded, said rod engaging said means at said end.

10. In a tool according to claim 9: there being a spring abutment within said tubular member, and a spring biased against said abutment and one end of said rod, said spring thereby holding said cutter and said tubular member in a retracted position in respect to said body.

11. In a tool for cutting into the sheath of a cable,

the combination comprising a body having a handle fixedly secured thereto, cable-locating means mounted on said body, said means being movable a quarter turn around said body from a first to a second position, and a finger loop pivotally carried by said means, said finger loop cooperating with said handle to facilitate the cutting of the sheath in either position of the cable-locating means.
